To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

A small ornamental figure is also combined with said groups of flowers and 15 leaves and crescent-shaped figures as shown. The border or upper portion of the design is composed of crescent-shaped figures with
